3 Claims. (Cl. 202—53)

This invention relates to a new and improved evaporator and a new and improved method or process for the evaporation of liquids. The invention is especially concerned with a process and apparatus for producing potable water from brackish well waters or brines.

One of the objects of the invention is to provide a new and improved apparatus and process for evaporating liquids which is especially adapted to the evaporation and condensation of water containing dissolved solids, such as, for example, brackish well waters and sea water.

Another object is to provide an apparatus and process of the type described in which the parts of the apparatus are less subject to scale and encrustation than is the case with conventional evaporating and condensing equipment.

Still a further object of the invention is to provide a process and apparatus of the type described which is simple and highly efficient in operation.

Other objects and advantages of the invention will be apparent by reference to the following description in conjunction with the accompanying drawing in which the single figure illustrates diagrammatically the best mode contemplated for the practice of the invention.

Briefly stated, the apparatus of the invention comprises (1) a heating unit in which water or other liquid to be evaporated is disposed and which is provided with a submerged combustion burner wherein the flame of the burner burns in direct contact with the liquid beneath the liquid level and the products of combustion from the burner are discharged directly into said liquid; (2) means for removing undissolved combustion gases from the heating zone; (3) means to transfer the hot liquid containing some dissolved products of combustion directly from said heating unit to a series of flash evaporators where the liquid emerges in such a way that a part of it flashes into vapor; (4) means to transfer the flashed vapors from the vapor space above the liquid in the flash evaporators to condensers; (5) means to recover the condensate; and (6) means to remove the residual liquid from the last evaporator in the series.

In the preferred operation of the invention the feed water to the burner unit is passed through the condensers before it is introduced into the burner unit, thereby serving to cool the vapors from the flash evaporator while the feed water itself is being preheated.

A preferred embodiment of the invention is the provision of a stripping tower in contact with the vapor space of the burner unit through which the feed water is preferably introduced and which contains suitable means to permit escape of gases but to prevent escape of most of the water contained with the gases that are generated in the heating unit by combustion. Since these gases contain some water, even after passing through the stripping tower, they are transmitted to an auxiliary condenser to remove as much of this water as possible before the gases are discarded. The resultant condensate or distillate is added to the condensate or distillate collected from the condensers for the flash evaporators.

An optional but preferred embodiment of the invention is to use the gases from the combustion unit to operate an ejector which is connected to the condensers and serves to remove air from the condensers. In prior practice these ejectors have usually been operated by means of steam.

The direct heating of the liquid by means of a submerged combustion burner makes it possible to operate with the liquid initially at a higher temperature and to effect a very substantial reduction in the heat requirements with decreased condenser and heat exchange surfaces. The use of a heating unit in which a submerged flame is brought directly into contact with the liquid also reduces scale deposits in the evaporators and consequently reduces maintenance and the time which the apparatus is out of operation for cleaning (usually referred to as "down time").

The drawing illustrates a system intended for use in making potable water from brackish waters, brines, and the like. In this system the heating unit generally shown at 1 contains a submerged burner 2 which provides a flame burning in direct contact with the liquid beneath the liquid level 3. The flame is produced by passing a suitable combustible fuel and a combustion supporting fluid, preferably natural gas and air, into the burner 2 by a suitable means generally illustrated at 4. Suitable submerged burners for use in the system of the present invention are disclosed in the prior art, particularly in U.S. Patents 2,118,479 and U.S. 2,432,942, and reference is made to these patents for a more detailed description and functioning of the burner units which do not form a part of the present invention.

In the heat generating unit 1 water is heated to a temperature just below the boiling point under substantially superatmospheric pressure, the conditions being sufficient to prevent the water from flashing into steam in the heating unit. It is preferable to operate this unit under a pressure of about 11 pounds per square inch gauge (25.7 pounds per square inch absolute) and to heat the water therein to a temperature of about 195° F.

The heated water is passed through a pipe or other suitable means 5 to the first stage flash evaporator generally indicated at 6. Flash evaporators are known per se and the particular construction of the flash evaporator does not form a part of this invention. The flash evaporator is preferably of a type in which the heated water is introduced near the bottom through slots in slotted horizontal pipes. The temperature of the water in the flash evaporator and the saturation pressure corresponding to the temperature of the water are lower than in the heating unit 1. In the six-stage flash evaporator system shown in the drawing, the temperature in the first unit or stage 6 is about 180° F. and the corresponding pressure about 7.5 pounds per square inch absolute. As soon as the liquid passing through the pipe 5 enters the flash evaporator 6 a portion of it flashes into steam which passes through pipe 7 to a condenser 8.

The residual liquid which does not flash into steam in the evaporator 6 is drawn off through pipe 9 to a second flash evaporator 10 and the condensate from condenser 8 passes through pipe 11 to a second condenser 12 which is associated with evaporator 10.

In the second stage of evaporation in the system illustrated in the drawing, the temperature of the flash evaporator 10 is around 165° F. and the corresponding pressure is 5.3 pounds per square inch absolute. Another portion of the heated water flashes into steam in this evaporator and passes through line 13 of the second condenser 12 where it is condensed. In a similar manner the residual water from the second stage of evaporation passes through line 14 to a third flash evaporator 15 which in the system illustrated is at a temperature of 150° F. and a pressure of 3.7 pounds per square inch absolute. The condensate from condenser 12 passes through line 16 and is mixed with the condensate from flash evaporator 15 in line 17 from which it passes into condenser 18.

The residual water from the third stage passes through

line 19 to a fourth stage evaporator 20 which in the system illustrated is at a temperature of about 135° F. and a pressure of 2.5 pounds per square inch absolute. The water which is flashed into steam in flash evaporator 20 passes through line 21 into condenser 22. The condensate from condenser 18 passes through line 23 and is mixed with the vapors from flash evaporator 20 or with the condensate from condenser 22.

The residual liquid from flash evaporator 20 passes through line 24 to a fifth stage flash evaporator 25 where another portion of the water is flashed into steam. The steam vapors pass through line 26 which connects with line 27 and are condensed in condenser 28. The temperature of the fifth stage evaporator is preferably around 120° F. at which the corresponding pressure is 1.7 pounds per square inch absolute.

The residual liquid from flash evaporator 25 passes through line 29 to flash evaporator 30 which is at a temperature preferably around 105° F. and the corresponding pressure of 1.1 pounds per square inch absolute. The steam which is flashed off in this last stage passes through line 31 where it is mixed with condensate coming from the fifth stage condenser through line 32 and is condensed in the sixth stage condenser 33. The final condensate is recovered through line 34 and the residual liquid is blown down or discarded through line 35.

As shown in the drawing, cooling of the condensers is preferably effected by passing the feed water which can be, for example, at an initial temperature of 80° F., countercurrently through the respective condensers via pipes 36, 37, 38, 39, 40, 41 and 42 to the heating unit 1. In this manner the feed water is progressively heated to a temperature of approximately 170° F. before it is introduced into the heating unit. The introduction of the feed water is preferably effected through a stripping tower 43 which also serves to remove entrained water from the gases that are given off by the combustion in the heating unit. This stripping tower preferably contains Raschig rings or other conventional devices for removing liquids from gases, the details of which the present invention is not specifically concerned. The gases passing upwardly from the stripping tower through line 44 are passed into a condenser 45 to remove a major proportion of the water contained therein. This condenser is cooled by cooling water at an inlet temperature of about 80° F. and an outlet temperature of around 100° F. The outlet cooling water can be discarded or used for some other purpose. The condensate or distillate is recovered through pipe 46 and added to the condensate or distillate recovered through pipe 34. The gas which passes through the condenser unit is preferably passed through a line 47 to an ejector 48.

The ejector 48 is connected by a suitable pipe 49 to pipes 50, 51, 52, 53, 54, and 55 of the condensers 8, 12, 18, 22, 28 and 33, respectively, to remove air from the condensers which is discharged to the atmosphere through pipe 56. Removal of this air is highly desirable from the standpoint of efficient operation and the use of the waste gases for this purpose is an important but optional feature of this invention.

While the invention is not limited to a system of any particular size, the following example illustrates the requirements for a unit having an output of about 100,000 gallons of potable water per day.

Example

The water used can be brackish well water containing 2,000 to 22,000 parts per million of dissolved solids or it can be water containing a higher concentration of dissolved solids, such as sea water.

As illustrated in the drawing, 383,040 pounds of feed water per hour initially at a temperature of 80° F. is introduced into the system through line 36 where it is first used in condensing vapors in the six-stage condenser 33. The temperature of the water is raised progressively

to 95° F., 109° F., 124.9° F., 139.8° F., 154.8° F., and 169.8° F. as it passes successively through condensers 28, 32, 18, 12 and 8 to feed water line 42 from which it is introduced into the stripping tower 43 and thence to the heating unit 1. The distillate recovered through pipe 34 as previously described amounts to about 32,330 pounds per hour. The blowdown discarded through pipe 35 amounts to about 349,170 pounds per hour. The heated liquid passing through pipe 5 from the heating unit at a temperature of about 195° F. amounts to about 382,000 pounds per hour.

In the heating unit approximately 8600 pounds per hour of dry gas and 2140 pounds per hour of water pass through the stripping tower 43 and line 44 to a condenser 45 where approximately 1870 pounds per hour of distillate are recovered. The cooling of the condenser 45 is effected with about 99,900 pounds per hour of water at a temperature of 80° F. About 8600 pounds per hour of gas and 270 pounds per hour of water at a temperature of about 110° F. pass through the line 47 and are used to operate the ejector 48.

The operation of the submerged burner 2 requires about 540 pounds per hour of fuel gas and 9150 pounds per hour of air. The heat requirements of the burner are approximately 12,050,000 B.t.u. per hour once continuous operation has begun.

The foregoing figures are based on calculations wherein the overall heat transfer coefficient of the condensers is assumed to be 500 B.t.u. per square foot per hour per ° F.

The invention is applicable to any multiple stage flash evaporator system of the type described in which there are two or more flash evaporators. Thus, the invention may be practiced with 2, 3, 4, 5, 6, 7, 8, 9 or 10 flash evaporators, depending to a considerable extent upon the space available and the output desired. Where only a small space is available the system can be operated with two flash evaporators. Such a system is particularly useful, for example, for producing fresh water from sea water in off-shore drilling operations. The invention is especially useful in arid areas where the water obtained from wells, for example, in Kuwait, is brackish and contains substantial quantities of dissolved solids. Water containing dissolved solids normally tends to form scale on the evaporators but by heating the water directly with combustion gases this tendency to form scale is reduced, apparently due to the action of the carbon dioxide present in such gases. Since the present invention also makes it possible to heat the feed water to higher temperatures initially, it is possible to use a six-stage evaporator where a five-stage evaporator would be employed in conventional heating where the water to be evaporated is heated by passing it through a heat exchanger heated by steam from a boiler. As compared with this conventional process the process of the present invention uses much less heat and requires less condenser and heat exchange surface. These factors, coupled with a reduction of scale deposits in the evaporators with consequent reduced maintenance and "down time," more than offset the added expense of an air compressor which is required to supply air to the submerged burner.

The invention is hereby claimed as follows:

1. A system for evaporation of liquids and condensation of the vapors therefrom comprising in combination a heating unit in which the liquid to be evaporated is disposed, said heating unit comprising a submerged combustion burner wherein the flame of the burner burns in direct contact with the liquid to be evaporated beneath the liquid level and the products of combustion from the burner are discharged directly into said liquid, means for removing undissolved gases from the combustion zone, a series of flash evaporators provided with a vapor space above the liquid, means to transfer the hot liquid containing said dissolved products of combustion directly from said heating unit to said series of flash evaporators where a part of the liquid is successively flashed into

flash vapors, a condenser connected to each said flash evaporator, means to maintain successively lower pressures and temperatures in said flash evaporators, means to transfer said flash vapors from said vapor space above the liquid in said flash evaporators to said condensers in each stage of evaporation where condensate is formed from said flash vapors, means to recover said condensate, means to transfer unvaporized liquid from one said evaporator to another in succession, means to transfer the products of combustion from the heating unit to operate an ejector connected to the vapor spaces of the condensers of each of the flash evaporators and serving to remove uncondensed gases from said condensers, and means to remove unvaporized liquid from the last evaporator in the series.

2. A method of making potable water from non-potable water containing dissolved inorganic salts which comprises heating said water in a closed vessel by means of a direct flame which burns in contact with the water beneath the liquid level and discharges the products of combustion directly into the liquid, withdrawing the heated water from said vessel and passing it successively through a series of flash evaporators at lower temperatures and pressures than the temperature and pressure at which the water is initially heated, successively condensing the vapors which are flashed from the water in each of said evaporators, recovering the condensate, utilizing undissolved products of combustion from the flame used in heating said water to operate an ejector connected to the condensers of the flash evaporators which ejector serves to remove uncondensed gases from said condensers, and removing the residual liquid from the last evaporator in the series.

3. A process of converting non-potable water to potable

water which comprises heating the non-potable water in direct contact with a flame which discharges products of combustion directly into said water beneath the liquid level in a closed vessel while maintaining superatmospheric pressure and a temperature of about 195° F., successively passing the heated water into a plurality of closed evaporating vessels at successively lower temperatures and pressures whereby vapors are flashed from the heated water condensing said vapors in each of said stages of evaporation, recovering the condensate, removing the residual water from the last stage of evaporation, utilizing the feed water successively for cooling in each stage of condensation in a direction countercurrent to the flow of the condensate, removing uncondensed products of combustion from the heating zone, stripping a portion of the water from said uncondensed products of combustion, condensing a portion of the remaining water from the products of combustion, recovering the condensate, and utilizing the products of combustion to operate an ejector connected to the condensation stages to remove uncondensed gases therefrom.
